 3 Claims. (Cl. 242—55.13)

The invention relates to an improved automatic threading magnetic tape recorder/reproducer of the type disclosed in the copending application of Friedrich Laa, Serial No. 125,603, now Patent No. 3,119,574 and assigned to the assignee hereof. Tape recorders of this type have a slide and associated catch for transferring a tape from a supply magazine to the take-up magazine or spool. Said slide is held in a guide whereby it can move from the vicinity of the tape supply to the take-up location. The catch on the slide engages a tag fixed at one end of the magnetic tape or at an end of a leader fixed to one end of the tape. In the arrangement according to the above-noted invention the catch is mounted on a pivotal slide and engages the tag in a plane normal to the axis of the spool whereas in accordance with this invention the catch is mounted in a plane parallel with the axis of the spool and is situated under the magazine or spool thereby eliminating the requirement of a pivotal slide.

The arrangement according to this invention offers advantages of simplified construction in that the catch may be rigidly connected to a non-pivotal slide and other special advantages in that the catch positively engages the tag of a magazine type supply spool upon insertion of the magazine onto or into the recorder/reproducer. Additionally, this invention provides a catch which is operative with many forms of tags and a different simpler magazine construction than shown in the above noted applications.

Also an important advantage of the improved slide and catch arrangement hereof is the ease with which the catch traverses the space between the supply and take-up locations passing the magnetic pick-up heads, driving spindle and pressing roller, without difficulty.

In the drawings, examples of presently preferred embodiments of the invention are illustrated schematically and only so much of the recorder/reproducer of the type noted is shown in FIG. 1 for purposes as an aid in understanding and yet distinguishing my invention from what is known.

The following description is given in connection with the drawing in which:

FIG. 1 is a plan view of a portion of a recorder/reproducer having incorporated therein the improvement according to this invention.

FIG. 2 is a side view partly in section, of a slide in a guide having a finger-shaped catch which is rigidly connected thereto;

FIG. 3 is a side view which shows a similar arrangement in which a pivotal catch is utilized;

FIGS. 4 and 5 are detailed views which serve to clarify the co-operation between the catch shown in FIG. 2 and a holder which serves as a magazine for the record carrier or tape; FIG. 4 being a plan view of the magazine, with its upper half removed, and the tag provided at the beginning of the tape. FIG. 5 illustrating how the magazine is placed on or into the recorder device, the magazine being shown as a cross-section of FIG. 4 taken along the line IV—IV.

In the device illustrated in FIG. 1 a supply and take-up magazine 13 and 42 respectively are shown, however, the take-up magazine 42 can be replaced by a take-up spool. The supply of magnetic tape is preferably housed

2

in a magazine 13 as shown at the left in FIG. 1. The magazines and/or spools are placed on conventional spindles (not shown) and between each magazine the magnetic pick-ups, driving spindle, etc. are located in any suitable manner.

5 As seen from FIG. 1, the tag 21 is in the path of the finger 2 mounted on a slide 1 and will be moved by said finger if the slide is moved along the guide path 6 whereby the tape is drawn from the supply spool 13. The take-up spool flange is suitably slotted to receive the tag 21 and draw it to the spool core upon rotation of the take-up spool in the known manner. The slide 1 may be moved manually or by other means such as disclosed in U.S. Patent 3,104,843.

10 15 The foregoing briefly describes the principle of operation of an automatic threading tape recorder of the type disclosed in the aforementioned application.

The improvement according to the invention is further shown in the arrangement illustrated in FIGS. 2 to 20 5 wherein a finger shaped catch 2 is fixedly arranged on a slide 1 located either below the tape deck or below the tape spools which may be elevated on bosses (not shown). The slide 1 is shaped in the form of a small rectangular or elongated block and made, for example, from metal, 25 synthetic material or the like.

It is assumed in the following description of the invention that the magazine is at the left hand side of an apparatus, hence also at the left hand side of the slide, and the winding device is at the right hand side as shown in FIG. 1.

30 35 The tape not shown in the figures emerges from the magazine leaving it in a plane normal to the plane of the drawing. The initial position of the slide 1 near the magazine is determined by a stop 3 provided on a plate 4 of the recorder/reproducer which supports the whole of the arrangement. From its initial position, the slide 1 is moved by a traction rope 5 (similar to rope 20 of Patent 3,104,843) to the right into its final position near the winding device. A guide path 6 for the slide is matched to the special form of the slide. In the examples described, the guide path 6 has a simple U-shape and bears on the plate 4.

40 45 An embodiment having a catch 32 which is pivotally arranged is shown in FIG. 3. The catch 32 is pivotal within a recess 7 of the slide 1 about a spindle 8 at right angles to the plane of the tape. An extension 9 is provided for pivoting the catch 32. In the initial position of the slide 1, as shown in FIG. 3, the extension 9 engages a stop 10 provided at the beginning of the guide path 6. When the slide 1 is moved to the right, the extension 9 engages the stop 10, rotates the catch about spindle 8 and

50 55 comes to lie on the base surface of the guide path 6, the catch 32 then assuming a perpendicular position. When the slide returns from the right, to its initial position, the catch 32 re-assumes the horizontal position shown in the figure. The plate 4 is provided with an aperture 11 in order that the movements of the extension 9 may take place unhindered.

The slide 1 may be moved forwards and backwards in various ways between its initial position near the magazine and its final position near the winding device. Thus, 60 the forward movement may take place either manually or by means of numerous types of drives deriving power from the drive for the apparatus. If the slide 1 has to be restored to its initial position immediately after the transfer of the tag 21 is terminated, a backsetting spring

The invention is applicable with many different forms of magazines and tags for the tape. In the embodiment shown in FIGS. 4 and 5, a tape-shaped record carrier 20 (FIG. 4) is housed in a supply magazine comprising two halves 13a and 14, the upper half of which is removed in FIG. 4, the lower half 14 only being shown. The halves of the housing have central apertures 15 by which a flanged tape spool 16 having a centering edge 17, is approximately centered thereon. Upon placing the magazine on the device, the magazine and its associated spool are fixed in known manner through the central aperture 18. Pins provided on the apparatus which can penetrate the housing of the magazine through apertures 19 determine the position of the magazine on the apparatus. The inner end of the tape 20 (FIG. 4), may be secured to the supply spool core, in any suitable manner and the outer end of the tape is provided with a tag 21, which is normally lodged in aperture 22 provided in the side wall of the housing. FIGURE 4 shows the tag 21 drawn out of the magazine for the sake of clarity. A space 25 is reserved in the housing of the magazine for accommodating the tag 21 of the tape. Said space is narrowed towards the interior of the magazine so that the tape 20, but not the extension 21 can pass through it. In addition to the aperture 22, the magazine wall 14 has an aperture 26 normal thereto so that the catch 2 or 32 can penetrate the housing of the magazine upon its placement on the apparatus and can emerge therefrom, upon displacement of the slide 1.

The height of the tag 21 attached to the tape is larger in its central portion 27 than the width of the tape 20. Thus, the tape 20 neither engages the housing of the magazine nor the slide, even though the tag extensions 27 within the space 25 lie on faces 28 or, during transfer, on the slide 1.

FIGURE 5 shows, by means of an arrow 23, how the magazine is placed on the device with its surface 14 parallel to the plate 4, the pins provided on the apparatus and entering the magazine through the apertures 19 determining, as previously mentioned, the ultimate position of the magazine. The initial position of the slide 1 and the catch 2, determined by the stop 3, is so chosen that the catch 2, upon placing the magazine on the apparatus, penetrates the space 26 behind the tag 21 located in recess 25. When the slide 1 is moved to the right, it correspondingly moves tag 21. With a tag as shown in FIG. 4, it is advantageous if the end adjacent the tape 20 be provided with a recess 29 in which the catch 2 is satisfactorily secured.

When using a pivotable catch, as shown in FIG. 3, for example, the aperture 26 has to be elongated and the initial position of the slide must be chosen so that the catch upon erecting itself, when the movement of the slide begins, is situated exactly behind the tag 21 upon reaching the perpendicular position.

The guide 6 for the slide may be supplemented, if desired, by a part 30 for guiding the tag 21.

As previously mentioned, the arrangement of the catch according to the invention is not limited to a single form of magazine and tag as above described. It is possible, for example, to form the catch as a bifurcated finger (not

shown) gripping the tag at a re-entrant part (not shown).

Irrespective of whether the catch is provided on the slide rigidly or in a pivotal manner, the magazine may be slid from one side into the apparatus instead of being placed on top of it as shown. The position of the magazine in the apparatus is then determined by lateral guides with stops (not shown) instead of pins 19 penetrating the housing as shown in the drawing.

When using a sliding magazine (not illustrated), the use of a pivotable catch affords the advantage that the magazine may be slid into the apparatus from any one of the sides of the recorder in contrast with a fixedly arranged catch which permits of introducing the magazine from only the top side.

Other modifications will be within the skill of those in the art and therefore, as indicated above, the appended claims are not to be taken as limited to the above described presently preferred embodiments.

I claim:

1. In a recorder/reproducer apparatus having a slide adapted to transfer magnetic tape from a supply spool to a take-up spool, the improvement comprising a guide member mounted on said apparatus and extending between said supply and take-up spools, a slide receivable in said guide member for longitudinal movement relative thereto, a catch member, means pivotally securing said catch member on said slide for movement from a retracted to an operative position, and said catch member engaging said guide member for pivotally moving it to its operative position upon movement of said slide.

2. In a recorder/reproducer apparatus having a slide adapted to transfer magnetic tape from a supply spool to a take-up spool, the improvement comprising a supply magazine housing said supply spool, means defining a recess in said magazine receiving a tag secured to the free end of said tape, a catch mounted on said slide, means defining an elongated aperture in said magazine for receiving said catch, a guide member mounted on said apparatus having one end adjacent said magazine and extending therefrom to a point adjacent said take-up spool, said slide being receivable in said guide member for movement between said magazine and said take-up spool.

3. Apparatus according to claim 2 wherein said slide comprises an elongated member having means defining a recess therein for receiving said catch, means for pivotally mounting said catch in said recess, said catch having an extension portion adapted to engage said guide member for pivoting said catch into engagement with said tag upon movement of said slide.
